UNITED STATES PATENT OFFICE.

JULIEN A. BRIED, OF OAKLAND, CALIFORNIA, ASSIGNOR TO H. C. WHITE COMPANY,
OF NORTH BENNINGTON, VERMONT, A CORPORATION OF VERMONT.

VELOCIPEDE BRAKE.

Application filed June 3, 1922. Serial No. 565,594.

This invention relates to a brake for the stand up type of velocipede generally, but particularly for the type shown in my patent of March 5, 1918, No. 1,258,391 and in my application for patent entitled Velocipede, filed the 3rd day of June 1922, which application has matured into Patent No. 1,565,545 on December 15, 1925.

It has for its principal objects, a simple powerful brake arranged to promote greatest efficiency and one that is extremely easy to remove for relining of the wearing surface, etc.

These objects are secured through the construction shown in the drawing accompanying this application in which Figure 1 is an elevation of the rear end of a velocipede of the frame construction shown in my latter patent referred to, which the near side and unrelated mechanism omitted, and shows the complete brake in place.

Figure 2 is a plan view of Figure 1 looking down and Figure 3 is a top view of the actuating foot lever only.

By further reference to the figures where-
in all similar members bear similar numbers, 1 shows a rear wheel axle, 2 a brake drum secured thereto, 3 a brake band surrounding a portion of the drum and pivotally connected at 4 to a foot lever 5.

At the other end of the brake band is a link 6 straddling the reach member 11 and pivotally hung to a bolt or pin 7, upon which the end of the lever 5 is also ful-
crumed.

The other end of the lever projects through a slot 9 in the center frame or guide 10 of the velocipede and is there available at 8 to the foot of the velocipede rider for operation.

At 11 is indicated the reach member of the velocipede and at 12-13 are the two operating treadles adapted to oscillate, when in operation, up and down on both sides of the reach member.

At 14 are indicated the sides of the vehicle which help to guide the treadles in their oscillatory paths.

It will be noted by particular reference to Figure 2 that the end 8 of the foot lever is located between the treadles 12 and 13 and in the elevation Figure 1 between the high and low points of oscillation of the treadles and just above the center of the reach piece 11.

The lever 5 is bifurcated at 15 (better shown in Figure 3) to straddle the reach member 11 and extends on each side of it to the fulcrum pin 7.

At 16 is shown a wire spring coiled about the pivot 4 of the lever and band connection through a slot in the center of the band, and having an extended piece 17 lying in the slot 9 of the frame piece 10 and impinging on the reach member to keep the lever 5 forced up and the brake in released position as shown.

The brake band 3 is lined with brake lining like any band brake as indicated at 18.

The operation of the device is as follows: 70
A rider on the vehicle has his feet on the treadles as indicated at 19-20 and while riding may slide either foot off the treadle when above the brake lever and bring a heel down upon the end 8 of the lever, de-
pressing it by his weight and thereby draw-
ing the band 3 tightly around the drum and
stopping the vehicle. This may be done
with either foot and after a few trials with-
out looking.

It will be observed that in order to re-
move this improved brake for relining, it
is only necessary to remove the single pin
or bolt 7 as the link 6 may then be swung
out and the entire brake worked backward to
release the end from the slot 9 and bodily
removed.

I claim:

1. In a velocipede of the character de-
scribed, an operating pedal pivotally sup-
ported on the vehicle and having a free end,
a vertically arranged guide against which
the free end of the pedal is movable up and
down, and a brake for the velocipede having
an operating lever projecting through and
guided by a slot in said guide.

2. In a vehicle of the character described,
a pair of pivotally supported operating
treadles each having a free end vertically
movable, a centrally arranged guide guiding
the free ends of the treadles thereagainst, and
a brake for the vehicle having an operat-
ing lever projecting through and guided by
a slot in said guide.

3. In a velocipede of the character de-
scribed, an operating pedal movable up and
down, a guide against which said pedal is
guided, a brake for the vehicle provided
with an operating lever projecting through
and guided by a slot in said guide, and a

spring on said lever normally forcing it against one end of the slot for releasing the brake.

4. In a juvenile vehicle adapted for operation by a rider in standing position, a brake drum concentric with the rear axle of the vehicle, a brake band adapted to engage the periphery of the drum, and a piv-

oted lever engaging the band at one end for drawing the band against the drum upon movement of the lever, said lever being arranged for operation by either heel optionally of the rider while standing upon the vehicle.

JULIEN A. BRIED.
